SLED-TYPE TOY FOR DOLLS

John W. Ryan, Los Angeles, and Jacob de Gelder, Torrance, Calif., assignors to Mattel, Inc., a corporation of California

Filed Feb. 1, 1967, Ser. No. 5,643

Term of patent 14 years

(Cl. D34—15)

FIG. 4

FIG. 5

We claim:

The ornamental design for a sled-type toy for dolls, as shown.
